ALL ANGLE ROTARY MITERER

Louis Frederick Ross, Kansas City, Mo.

Application June 20, 1935, Serial No. 27,607

2 Claims. (Cl. 144—134)

This invention relates to a rotary mitering machine which is mainly designed for cutting miters for framing borders for use in setting type forms in the printing industry.

5 The general object of the invention is to provide foot operated means for feeding the work to the cutting means so as to leave both hands of the operator free for handling the work on the cutting table and to make it possible for cutting 10 the work at any desired angle including the conventional 45 degree angle.

This invention also consists in certain other 15 features of construction and in the combination and arrangement of several parts, to be herein-after fully described, illustrated in the accompanying drawings and specifically pointed out in the appended claims.

In describing the invention in detail, reference 20 will be had to the accompanying drawings wherein like characters denote like or corresponding parts throughout the several views, and in which:—

Figure 1 is a perspective front view of the machine.

25 Figure 2 is a top plan view thereof.

Figure 3 is a section on the line 3—3 of Figure 2.

Figure 4 is a fragmentary bottom plan view of the table.

30 Figure 5 is a section on the line 5—5 of Figure 2.

Figure 6 is a section on the line 6—6 of Figure 5.

Figure 7 is a section on the line 7—7 of Figure 2.

35 Figure 8 is a view showing a supplemental member which might be used in place of the triangle.

In these drawings, the numeral 1 indicates a base and the numeral 2 indicates a post rising from the base and having attached to its upper end a horizontal member 3 from which rise the bearing members 4 for the shaft 5. Tapered bushings are provided for these bearings, one bushing having its small end exteriorly threaded to receive the nut 7 for taking up wear in the bushing and the other bushing is engaged by a cap 8 which surrounds a reduced externally threaded part 9 of the shaft 5, said shaft being adjusted to take up wear of the bushing through the means of a nut 10 threaded on the reduced part 9, the nut being held in place by the lock nut 11, these features being more particularly shown in Figure 7. The shaft is provided with 55 a socket for receiving the shank on the cutting

member 12 which is preferably of the spiral type, a hole 13 being formed in the shaft at the inner end of the socket so that a tool can be driven into the hole to force the cutting member out of the socket. Grease cups 14 are provided on the bearing members 4 for supplying lubricant to the bushings and those parts of the shaft engaged thereby and a pulley 15 is attached to the shaft between the bearing members 4 for receiving a belt 16 which passes over a pulley 17 attached 10 to the shaft of a motor M which is attached to the base 1 as shown in Figure 1.

A tubular member 18 is supported for vertical movement on the upper part of the post 2 and is formed with a bracket 19 which extends 15 outwardly and upwardly and has a horizontal part 20 at its upper end which is formed with the opening 21. A block 22 having an opening 23 therein is seated on the horizontal part 20 and a segmental-shaped table 24 is supported on the 20 block 22 and this table has a bolt 25 passing therethrough and said bolt passes through the openings 23 and 21 and is provided with a thumb nut 26 on its lower end which bears against a washer 27 which engages the lower face of the 25 horizontal part 20. A screw 28 is threaded into a hole in the front end of the block 22 and has a groove therein as shown at 29 which receives the forked end of the depending part 30 of the table so that by loosening the nut 26 and then 30 turning the screw 28 the table can be moved toward or away from the cutting member 12 which fits in the corner of the space formed by the peculiar shape of the table, as shown in Figure 2.

Plates 31 are attached to the sides of the block 35 22 and depend therefrom and the depending portions are provided with threaded holes for receiving the screws 32 which engage the horizontal member 20, as shown in Figure 6. Thus by loosening the nut 26 and adjusting these screws 32 40 40 the block and the table 24 can be adjusted sideways.

The top of the block 22 is formed with the keyways 33 which receive the keys 34 of the underface of the table for preventing relative rotary 45 movement of these parts while permitting the table to be adjusted on the block toward and away from the cutting member. The keyways and keys also cause the table to move with the block when the block is adjusted by the screws 50 32. Of course, after the table has been adjusted the nut 26 is tightened to hold the parts in adjusted position.

The table is formed with a depending part 24' which carries the keys and the parts 30 as shown 55

in Figure 4, this part being of rectangular shape and having a central opening 24" therein.

A foot pedal 36 is connected to one end of a shaft 37 journaled in a bracket 38 on the base 5 and an arm 39 is connected to the other end of the shaft and a rod 40 has its lower end connected with the arm 39 and its upper end to the bracket 19 as shown at 41 so that depression of the pedal 10 will raise the tubular part 18, the bracket 19 and the table assembly. A bar 42 passes through a socket 43 carried by a vertically arranged lug 44 on the upper part of the post and said bar is held in adjusted position in the socket by a screw 45. The lower end of the bar is adapted to engage a 15 shoulder forming part 46 on the tubular part 18 so as to limit upward movement of the tubular part 18 and the table assembly. Thus by adjusting the bar 42 in the socket 43 the table can be stopped in its upward movement at any desired 20 point. A guide 47 is formed on the tubular part 18 and engages the lug 44 for keeping the table in proper position in relation to the cutting member 25 as the tubular member and the table assembly move upwardly and downwardly.

25 A straight edge A has a web 48 at its central portion through which passes a screw 49, the head 50 of which slides in a concentric groove 51 on the top of the table so that the angle member 30 can be adjusted on the table by loosening the nut 52 and moving the member to cause the head to slide in the groove. One arm of the member A carries the adjustable guide 53 which is held in adjusted position by the set screw 54 and this arm also carries a ledge 55 to support the outer 35 end of the work piece when said piece extends beyond the area of the table.

Instead of using the straight edge A the straight member B shown in Figure 8 may be used, this member being formed with the extension 55 having a hole 56 therein in which the screw 49 is adapted to be passed. This member 40 is also provided with the adjustable gauge 52 and the ledge 54. Said member is formed with the vertical wall 57 and horizontal walls 58.

45 Thus it will be seen that the operator in placing the material to be cut on the table can use both hands to adjust the material and then by depressing the pedal the table with the work piece thereon is raised against the cutting member. By

loosening the nut 51 the member A can be adjusted to miter or cut the work piece at any desired angle and by adjusting the stop rod 42 the device can be adjusted to cause the cutting member to cut entirely through the material or only 5 partly through the same.

This machine makes it possible to form a large variety of border designs from stock of any thickness within reason.

A trough 60 is carried by the table assembly 10 for receiving the cuttings from the member 12.

It is thought from the foregoing description that the advantages and novel features of the invention will be readily apparent.

It is to be understood that changes may be 15 made in the construction and in the combination and arrangement of the several parts, provided that such changes fall within the scope of the appended claims.

What is claimed is:—

20

1. In an apparatus of the class described, an upright, a horizontal shaft journaled in the upper end of the upright, a cutting member carried by the shaft, a table for supporting the work piece to be cut, a concentric groove in the table, a straight edge slidably mounted in the groove, and means for adjusting the table both longitudinally and laterally relative to the cutting member, whereby the work piece may be cut at all angles. 25

2. In an apparatus of the class described, an upright, a horizontal shaft journaled in the upper end of the upright, a cutting member carried by the shaft, a tube slidably mounted on the upright, a table mounted on the tube and having a cut-away portion therein arranged under the cutting member, a foot pedal connected to the tube for raising the table, and means for adjustably limiting the upward movement of the table to permit the depth of the cut caused by the action of the cutting member on the work piece to 40 be controlled, said means comprising a lug mounted on the upright and having a socket extending therefrom, a bar adjustably mounted in the socket, means for retaining the bar in adjusted position, a shoulder integral with the tube 45 and adapted to be engaged with the lower end of the bar, and means for guiding the vertical movement of the tube.

LOUIS F. ROSS.
